CLAIM

The ornamental design for an ambidextrous holster with hood, as shown and described.

DESCRIPTION

FIG. 1 is a front elevational view of the ambidextrous holster with hood of my invention;

FIG. 2 is a rear elevational view thereof;

FIG. 3 is a left side elevational view thereof, the opposite side being a mirror image of the side shown;

FIG. 4 is a top plan view thereof; and

FIG. 5 is a bottom plan view thereof.
